UNITED STATES PATENT OFFICE.

JOSEPH H. LYNCH, OF ASBURY PARK, NEW JERSEY.

GOLF TEE.

Application filed August 18, 1925. Serial No. 50,966.

My invention relates to portable golf tees and has for its object the embodiment of certain characteristics in the tee that will make the device not only serve as a portable tee but also have other functions purposing to aid the player in his stance and his drive.

Every golfer knows that the most important maxims of the game are "Keep your eye on the ball", and "Keep your head down until you see the place where the ball was before it was struck."

Simple as these instructions seem they are not so easily carried out in practice and it is one object of the present invention to facilitate adherence to these rules. A famous golfer has said "A topped shot is usually caused by either taking the eye off the ball, or looking at the wrong part of the ball." The eye should be focused not on the top of the ball but on the side where the ball is to be struck. According to my present invention I make the tee preferably of soft rubber with a substantially flat piece for a base from which rises a tee proper having a concave top to hold the ball. The base piece is fashioned with an extension in line with the tee proper, designed to show the direction of the drive, which extension is preferably in the form of an arrow to more evidently indicate its purpose. At right angles to this extension and in line with the tee proper, I form two other extensions, one on each side, preferably also of arrow shape to aid the player to take the proper stance. By looking along the line of these arrows the golfer can accurately place himself so that his club will swing parallel with his feet. The line of sight giving a much more accurate means of determining the correct position than the line of flight at right angles thereto would. Only one such right angle extension is required but I prefer to have two as two will give better alignment and also make the tee serve equally well for left handed players.

To aid the player in keeping his eyes focused on the proper place, I make a conspicuous mark on the base diametrically opposite the line of flight arrow and at a distance from the tee proper, such that it will show just below the face of the ball that is to be struck. I preferably make this mark conspicuous by coloring it bright red as this color more than any other holds the attention of the eye. This mark therefore, not

only serves the purpose of keeping the eye on the ball but holds the eye focused on the right part of the ball.

To act as an aid to the player in keeping his head down and not trying to anticipate the ball in its flight, I prefer to color also the cup part of the tee upon which the ball rests. This color should be also conspicuous but different from the focusing mark. It may for example, be bright yellow. The instructions will therefore, read to keep your eye on the red spot until you see the yellow spot, after which you may follow the ball in its flight.

A tee embodying my invention is shown in the accompanying drawings, in which:

Figure 1 is a plan view and,

Figure 2 is a side elevation partly in section.

The tee is molded of soft rubber and comprises a flat base piece 1, from a central point 2 of which rises a protuberance 3 to form the tee proper. This tee has a concave top 4 to form a cup for the ball which top is preferably colored yellow or some other conspicuous color.

In line with the tee the base piece 1 is extended in the shape of an arrow 5 which is intended to point in the desired direction of flight. A ridge or line 5' along the center of the extension providing a means of more accurate alignment that the arrow alone would. At right angles to the arrow 5 are two other preferably shorter arrows 6 one on each side of the tee to serve as a guide to the player in taking his stance, as he will know that if, in looking straight in front, he is in line with these arrows, he will be in position to have his swing tangential to the line of flight, when his club hits the ball. It is a fact that this right angle line gives a much more accurate guide to proper stance than a line parallel with the line of flight.

A center ridge or marking line 6' may also be used here to more accurately determine the right-angle line.

At a point diametrically opposite the direction arrow 5, I form an extension 7 of the base, which is colored preferably bright red and being in line with the back face of the ball forms a conspicuous mark that will hold the eye of the player focused on just the right point of the ball to avoid such errors as topping, slicing or hooking. The

outline of a golf ball showing its size relative to the tee is indicated by the dot and dash line 8.

In using the tee the player will place the same with the arrow 5 pointing in the direction it is desired to have the ball driven, and then placing a ball in the cup 4 will take his stance so that he is looking straight along the right-angle line 6-6, and then 10 make his drive with his eyes focused on the red spot 7 and keep his eyes so focused until he sees the yellow spot on top of the tee after which he may follow the flight of the ball. The tee in this way acts as a continual 15 reminder of the maxims of driving, as well as an excellent guide to the making of accurate play.

I claim:

1. A portable golf tee characterized by a 20 protuberance serving as a ball support, a pointer in line with the center of the tee to indicate the direction of flight, a second

pointer fixed at right angles to the first pointer adapted to show the proper position for the player, and a conspicuous colored 25 mark diametrically opposite the pointer on the other side of the protuberance adapted to show just behind a golf ball resting on the support.

2. A portable golf tee characterized by a 30 protuberance serving as a ball support and having its top surface colored to distinguish it from the other surfaces of the tee, a pointer extending in line with the protuberance and adapted to point the direction of the line 35 of flight, a pointer at right angles to the first pointer adapted to act as a guide for the player's stance, and a conspicuous mark on the side of the protuberance diametrically opposite the line of sight pointer to aid in 40 focusing the eye of the player on the place where the ball is to be struck.

JOSEPH H. LYNCH.
